UNITED STATES PATENT OFFICE.

WILLIAM F. DESTER, OF NEWARK, NEW JERSEY, ASSIGNOR TO U. S. TOOL CO., INC., OF EAST ORANGE, NEW JERSEY, A CORPORATION OF NEW JERSEY.

SELECTIVE IGNITER FOR MULTIPLE GAS BURNERS.

Application filed April 20, 1927. Serial No. 185,124.

This invention relates to gas burners as applied to stoves, heaters and the like when a plurality of independent, spaced burners are to be selectively ignited, singly or in 5 series.

Such ignition is commonly accomplished by grouping the burners about a central, constantly burning pilot light, operating a valve to increase the volume of gas to the pilot and 10 trusting to chance that the several flames extending from the pilot may ignite the burner desired and which has its valve opened to admit gas.

It is apparent that such procedure is slow, 15 uncertain, inconvenient and wasteful, requiring the use of both hands to operate.

To evade many of these disadvantages is the main object of the present invention, the device avoiding the use of a flash valve on 20 the pilot and the waste of gas consumed by streams of flame directed uselessly outward.

These and other advantages, which will later appear, are accomplished by the simple and practical construction and arrangement 25 of parts hereinafter described and exhibited in the accompanying drawings, forming part hereof, and in which:-

Figure 1 is a plan view showing a conventional arrangement of burners connected in 30 accordance with the invention.

Figure 2 is a vertical sectional view taken through the pilot burner and drawn to an enlarged scale.

Figure 3 is a transverse sectional view taken 35 on line 3—3 of Figure 2.

Figure 4 is a similar sectional view of the pilot burner taken on line 4—4 of Figure 2.

Figure 5 is a fragmentary plan view of a burner inlet control connection, partially 40 in section.

Figure 6 is a sectional view taken on line 6—6 of Figure 5.

Figure 7 is a perspective view of the pilot burner cover.

Figure 8 is a similar view of the burner cap.

In the layout shown in Figure 1, a capped header is designated by the numeral 10, the same being connected with a gas supply by the pipe 11.

Set in register in the header are a plurality of spaced cock bodies 12, provided with control plugs actuated by handles 13, these bodies containing passages 14 having plugs 15 fixed rigidly at their outer ends, these plugs having conical points and containing narrow

slits 16 through which gas emerges when the cock is open.

Adjustably engaged by threads on the ends of the bodies are caps 17 having conical axial openings 18 by which the outward flow of 60 gas is controlled, these caps being positioned partially within the open bell-shaped mouths 19 of conductors 20 leading one to each of the several burners 21^a, 21^b, 21^c and 21^d.

Extending at right angles from the cock 65 bodies 12 are branches 22 containing openings 23 communicating with the chambers 14 beyond the cock plug, these openings being adjustable by needle valve screws 24 whereby the passages are adjusted.

At the outer end of the extensions 22 are double coned enlargements 25 engaged by sleeves 26 threaded on to small tubes 27^a, 27^b, 27^c and 27^d for which they act as unions.

Extending at right angles from the header 75 10 intermediate its length is a branch 28 connected by a union 29 to a tube 30 bent upwardly at a right angle at a point substantially intermediate the four burners, the tube 80 entering a cup 31, having a plurality of air openings 32 in its bottom, and leading to a constantly burning pilot light 33.

The auxiliary pipes 27^a, 27^b, 27^c and 27^d are bent as best seen in Figures 1, 2 and 3, to enter the cup 31, pass through the perforated 85 cap 34 having a central opening 35 in register with the pilot 33, where the pipes are further bent into a horizontal plane, so that they pass over the opening 35 in staggered offset relation, finally leading outwardly 90 through recesses 36 in a pilot cover 37, to their respective burners 21^a, 21^b, 21^c and 21^d.

The pipes 27^a, 27^b, 27^c and 27^d are provided in their undersides with perforations 38 extending from a point where the same passes 95 over the pilot 33 to their outer free ends at the burners.

Thus, if it is desired to light the burner 21^a, it is merely necessary to open the corresponding valve handle 13, permitting gas to flow to 100 the burner 21^a and at the same time through the auxiliary pipe 27^a.

When the gas in the pipe 27^a passes over the pilot light 33, it will, because of the perforations 38, become ignited, the flame travelling 105 along the remainder of the pipe 27^a, until it reaches the burner 21^a where it will ignite the gas issuing therefrom.

Thus it may be seen that a pilot light has been disclosed, by which any single or series 110

of burners may be ignited instantaneously, in a convenient manner and without a waste of gas.

It will also be noted that the burner is 5 much safer than the present flash pilots inasmuch as there are no exposed outwardly flaring flames when supplying the burners with fuel as is the case if a flash pilot is used.

The foregoing disclosure is to be regarded 10 as descriptive and illustrative only, and not as restrictive or limitative of the invention, of which obviously an embodiment may be constructed including many modifications without departing from the general scope 15 herein indicated and denoted in the appended claims.

Having thus described my invention, what I claim as new and desire to secure by Letters Patent, is:—

20 1. In a pilot burner for a plurality of gas burners each having independent controls, a pilot burner connected with the source of gas supply, a cup surrounding said pilot burner,

a perforate cap over said cup, a plurality of pipes one for each main burner arranged over 25 said cap and provided with perforations, said pipes having controllable connections with the gas supply source at one end and extending to the main burners at their opposite ends, and a cover over said pipes and pilot burner. 30

2. In a device for selectively igniting a plurality of gas burners, the combination with a header having controllable connections with each burner and a pilot burner in open communication with the header, of branches leading from each of said burner connections over said pilot burner, said branches having a straight row of perforations in their under sides to permit gas to be ignited by the pilot and convey flame to the burner with which it 40 communicates, and an inverted cup covering said branches over the pilot burner.

This specification signed this seventh day of December, 1926.

WILLIAM F. DESTER.
